UNITED STATES PATENT OFFICE.

ALBERT MALCHOW, OF FORT SMITH, ARKANSAS.

DESIGN FOR A CASTER.

No. 38,817.

Specification for Design.

Patented Sept. 17, 1907.

Application filed July 31, 1907. Serial No. 386,486. Term of patent 7 years.

To all whom it may concern:

Be it known that I, ALBERT MALCHOW, a citizen of the United States, residing at Fort Smith, in the county of Sebastian, State of Arkansas, have invented a new, original, and ornamental Design for Casters, of which the following is a specification, reference being had to the accompanying drawing, forming a part thereof.

The figure is a perspective view of a caster, showing my new design.

I claim,

The ornamental design for a caster, as shown.

ALBERT MALCHOW.

Witnesses:

BURLEY C. JOHNSTON,
JNO. VAILE.
